UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

CORNER BRACKET.

Application filed March 4, 1924, Serial No. 696,808. Renewed May 16, 1927.

My invention relates to improvements in corner brackets for securing wire lath to the convexed corners of the perpendicular walls of stuccoed structures, although also applicable to other corners and convexed edges of such structures, and one of the objects of the present invention is the provision of corner brackets secured in longitudinally spaced apart order to the convexed corners 5 of stuccoed structures for spacing wire lath a distance outwardly from the apexes thereof; a further object is the provision of a corner bracket embodying a length of wire having its intermediate portion formed into 10 a lath supporting bar, and having other portions formed into oppositely inclined wall bars adapted to straddle the apex of the corner and secured to opposite sides thereof, for supporting the lath supporting bar 15 outstandingly therefrom and parallel therewith.

With the foregoing and still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of 20 what is claimed without departing from the spirit of the invention.

In the accompanying drawings—

Figure 1 is a perspective view of portions 35 of two rectangularly intersecting walls of a stuccoed structure, with my improved brackets attached to the corner thereof, and with lath and stucco applied to the lower portions thereof;

Figure 2 is a sectional view on line 2'—2', Fig. 1;

Figure 3 is an upper end view of one of the brackets disposed in engagement with the corner of a structure, preparatory to attaching it thereto;

Figure 4 is a view similar to Fig. 3 but with the bracket in its permanent position attached to the corner;

Figure 5 is a view in elevation of a fragmental section of the left-hand side of a corner, and one of the brackets attached thereto;

Figure 6 is an elevation of the right-hand side of the corner, and one of the brackets 55 attached thereto; and

Figure 7 is a perspective view of one of the brackets.

Referring to the drawings in detail, throughout which like reference characters designate like parts;

The numeral 1 designates the wall studs, and 2 the wall sheathing, of the rectangularly intersecting portions of two perpendicular walls of a stucco structure.

The wall sheathing 2, which may comprise ordinary siding boards, wall-board composition, or tar paper or other suitable wall covering, is preferably secured across the face of the studs 1 in close-jointed order so as to form as nearly as practicable a continuous and uninterrupted backing for the reception of the stucco composition.

3 designates my improved bracket, which is formed of wire and comprises a lath supporting bar 4, which has its ends struck inwardly thereby forming comparatively short arcuated spacing bars 5, which are disposed in the same plane and terminate in laterally inclined loops or wall bars 6, the free ends of which cross the plane of the spacing bars 5 and extend a distance therebeyond at an angle of 45 degrees therewith forming wall bars 7, which have their free ends bent to one side to form fastening prongs 8, the latter disposed in a plane 70 parallel with the plane of the loops 6.

The planes of the loops or wall bars 6 cross the planes of the wall bars 7 at right angles, and at their point of intersection cross the plane of the spacing bars 5 at 80 angles of 45 degrees therewith.

The outer ends of the loops 6 are laterally extended to provide nail openings 9.

The brackets 3 are disposed to ride the apex of the corner with the lath supporting bar 4 extending parallel therewith and equi-distant from the plane of either wall, and are preferably attached by disposing them, one at a time, in the position shown in Figure 3, namely, with the loops 6 engaging the face of the sheathing 2 on one side of the corner and the pointed ends of the prongs 8 engaging the sheathing on the opposite side thereof, and then driving the prongs therewith until the bars 7 seat firmly 100 against the face thereof (see Figure 4), after which nails 10 are driven through the openings 9 into the sheathing for further securing the bracket.

The brackets 3 are disposed astraddle of 110

the apex of the corner in longitudinal alignment, preferably in spaced apart order, whereby the supporting bars 4 will provide outstanding furring means for receiving the wire lath 11 and holding it at a distance outwardly from the face of the wall sheathing 2. This lath is supported along the intermediate portions of the walls by means of furring tubes 12 cooperating with fastening staples 13. Obviously other furring means may be substituted for the tubes 12, such for instance as the Sullivan wire fasteners, Patent No. 1,435,429, or the Weber Patent No. 1,311,932, or any other suitable furring devices that may be found expedient and practicable.

14 designates the stucco composition, which is adapted to be spread against the wall sheathing 2 and on and around the lath 11 and brackets 3.

While numerous devices have been invented for securing and spacing the lath along the intermediate portions of the walls, none of which provide for adequate spacing along the corners, which has resulted invariably in crushing and bending the lath out of alignment when stretching it therearound, thereby rendering it difficult to properly build up the stucco material along the corner for forming a true and straight outer face therefor.

If desired, the nails 10 can be omitted and the prongs 8 alone depended on for securing the brackets to the sheathing; or, if preferred, the prongs may be dispensed with and the nails employed for attaching the brackets.

I claim:

1. A corner bracket comprising, a lath supporting bar, spacing bars at either end thereof, oppositely disposed laterally inclined wall bars at the inner ends of said spacing bars.

2. A corner bracket comprising, a lath supporting bar having at each end a spacing bar, terminating in a loop having an extension provided at its free end with a fastening prong.

3. A corner bracket comprising, a lath supporting bar having its ends bent over to form spacing bars, said spacing bars dis-

posed in the same plane and terminating in a pair of loops inclining away from said plane, and extensions on said loops disposed on the opposite side of said plane and inclining therewith.

4. A corner bracket comprising, a lath supporting bar having one end struck to one side to form a spacing bar, said spacing bar terminating in a loop inclining outwardly from the plane of the spacing bar and having an extension crossing said plane and extending a distance therebeyond at an incline therewith, and means on the opposite end of said lath supporting bar adapted to engage a support for supporting said end.

5. A corner bracket formed of a length of wire and comprising, a lath supporting bar terminating at each end in a loop, the free ends of said loops terminating in extensions, and a nail projecting through each of said loops.

6. A corner bracket formed of a length of wire and comprising, a lath supporting bar having at each end a loop, the free ends of said loops terminating in extensions, said loops disposed at right angles with said extensions, said bar disposed at a distance outwardly from the intersections of said loops and extensions.

7. A corner bracket formed of a single length of wire and comprising, a lath supporting bar having at each end a loop, the free ends of the loops terminating in extensions disposed in a plane approximately at right angles with the plane of said loops, the free ends of said extensions formed into fastening prongs.

8. A corner bracket formed of a length of wire and comprising, a lath supporting bar having at each end a loop, the free ends of said loops terminating in extensions, said extensions disposed at right angles with said loops, said lath supporting bar disposed in a plane crossing the intersections of said loops and extensions at an angle of approximately 45 degrees with said loops and extensions.

In testimony of the foregoing being my own, I have hereunto affixed my signature this 27th day of February, 1924.

GEORGE F. VOIGHT.
